UNITED STATES PATENT OFFICE.

BARNET GROSSBARD, OF SAN FRANCISCO, CALIFORNIA.

MOTOR ATTACHMENT FOR SEWING MACHINES.

Application filed December 11, 1926. Serial No. 154,121.

This invention relates to motor attachments for sewing machines, and has for its principal object to provide a clutch mechanism of novel construction, readily applied to the drive shaft of a motor and the operating wheel of a sewing machine.

Another object of this invention is to provide a motor attachment for sewing machines, having therein a novel double gripping clutch mechanism adapted to satisfactorily control the speed at which the sewing machine is to operate.

Another object of the present invention is to provide a novel clutch mechanism adapted for use in connection with a sewing machine and a motor, whereby the sewing machine may be conveniently thrown into and out of operation and may be satisfactorily regulated as to speed.

A further object of the present invention is to provide a novel clutch mechanism adapted for use with a motor and a power driven machine whereby the machine may be operated by the motor at various speeds.

A further object of the present invention is to provide a novel clutch mechanism adapted for use with a motor and a power driven machine whereby the machine may be made to operate at various speeds by the motor or the motor may be permitted to operate independently of the machine.

Other objects more or less apparent will be disclosed and described in the following specification and shown in the accompanying drawing, in which:

Fig. 1 is a bottom plan view of an attachment for sewing machines embodying my invention;

Fig. 2 is a side view of the same showing the clutch member in cross section and in a disengaged position; and

Fig. 3 is an enlarged sectional view of clutch member showing the same in an engaged position.

Referring to the drawings, the numeral 1 designates a motor of the usual type and construction, having a shaft 2. Detachably secured to the shaft 2 by a set screw 3 is a wheel 4. Fitting around the wheel 4 is a fly wheel 5, having a shaft 6 integrally attached thereto which is rotatably located inside a bearing 7. The bearing 7 is held in place on a base 8 by a support 9 which fits inside a projection 10 on the base, the said

support being held in place and adjusted by bolt screw 11.

Located between the wheel 4 and the inside surface of the fly wheel 5 is a circular disc 13, which is secured to the fly wheel by a screw 14. The circular disc 13 is constructed from any suitable material such as tin and is adapted to bend into a cone-shaped position, as will be described hereinafter.

Located inside the fly wheel 5 is a circular shaped gripping pad 15, constructed from leather or other suitable material, having its inside circumferential part 16 positioned between the outer circumferential part of the circular disc 13 and the inner surface of the said fly wheel. The outside part of the pad 15 projects outwardly beyond the circular disc 13 and is adapted to contact with the inside surface

of wheel 4. When the screw 14 is screwed into the fly wheel 5 the circular disc becomes slightly cone shaped owing to the fact that its outside circumferential edge is not permitted to be moved inwardly with its central part because of the location between it and the fly wheel of the inside circumferential part 16 of the circular disc 15. The outer circumferential edge of the circular pad 15 is also caused to project outwardly toward the wheel 4 when the screw 14 is screwed into the fly wheel 5, and it is this part of the said pad that firstly contacts with the said wheel 4 when the clutch member is moved toward the same, as will be explained herein. The contact between the fly wheel

5, the circular gripping pad 15 and the circular disc 13 is loose enough to permit the movement of any one of these parts independently of the other, thereby affording a means for transferring motion from the wheel 4 to the fly wheel 5 in a gradual manner.

The motor 1 is attached to the base 8 by screws 17 and the base is suitably attached by bolts or other means to a sewing machine or other mechanism to be operated.

Located around the shaft 6 between the bearing 7 and the fly wheel 5 is a sleeve 18 which is adapted to maintain the fly wheel in its proper position in reference to the bearing 7.

Located at the end of the shaft 6 within an indentation therein, is a steel ball 19, the same being movably held on the end of the said

shaft by flanged piece 20 which fits on the end of the said shaft and is suitably secured thereto by a screw or other means.

The base 8 is provided with a projection 21, having therein a suitable recess for the insertion of a bar 22, the same being adjustably held within the projection by a set screw 23.

Pivoted on the bar 22 by means of a pin 10 24 is a lever 25 which has an extension 26 thereon, the said extension projecting slightly beyond the ball 19 and being adapted to come into contact with the same.

Forming a part of the bar 22 is an extension member 27, to the end of which is attached one end of a spiral wire spring 28. The other end of the spring rests against the lever 25 and tends to keep the extension 26 from pressing against the ball 19.

Attached by a screw 29 to the upper part of the lever 25, just below the fly wheel 5 is a leather piece 30 which serves to prevent the revolving of the fly wheel when the device is not to be operated.

An extension rod 31 connects the lever 25 and a foot pedal or other device for throwing the machine to be operated through belt 32 into or out of operation.

When the attachment is out of operation 20 the spring 28 forces the lever 25 upwardly, thereby causing the extension 26 to be released from contact with the ball 19, and the leather piece 30 to press against the fly wheel 5, thereby preventing the said fly wheel from revolving.

To cause the sewing machine or other mechanism to operate, the rod 31 is pulled in a downward direction, thereby carrying with it lever 25, which causes the extension 40 26 to move inwardly and be forced against the ball 19. The wheel 4 which is secured to the shaft 2 revolves with the said shaft upon the movement of the motor. As the ball 19, the shaft 6, the fly wheel 5, the circular disc 45 13 and the gripping pad 15 are forced inwardly by the extension 26, the outer circumferential edge of the gripping pad 15 firstly comes into contact with the wheel 4, thereby causing the fly wheel to revolve with comparatively slow speed. As the pad 15 is forced inwardly still further, a greater part 50 of its surface is caused to contact with the wheel 4, and the fly wheel is thereby made to move faster. When the clutch mechanism is 55 in the position shown in Fig. 3 the gripping pad 15 is in firm contact with the wheel 4, and the maximum amount of motion is being transferred to the fly wheel.

The construction of the clutch mechanism 60 with the gripping pad 15 located around the circular disc 13 in the manner described, enables the operation of the sewing machine or other mechanism at any desired speed, dependent solely upon the downward force applied to the rod 31.

The attachment herein shown and described may be readily applied to or removed from the driving shaft of a motor, and the construction is such that an attachment of this form can be readily applied to practically all existing types of sewing machines, and also to many other types of machines which are to be operated at various speeds by a motor. I therefore do not desire my invention to be confined in its use to sewing machines alone, nor to be limited to the exact construction herein shown, but desire it to be included within the spirit of the appended claims.

Having described my invention, what I claim is:

1. A motor attachment of the class described comprising, in combination with a motor, a wheel secured to the shaft of a motor, a fly wheel having a shaft thereon, a disc attached to the fly wheel, a gripping pad located in the fly wheel with a part thereof extending between the disc and the fly wheel and another part thereof projecting beyond the disc, and means for moving the fly wheel whereby the gripping pad may be brought into contact with the first mentioned wheel.

2. A motor attachment of the class described comprising, in combination with a motor, a wheel secured to the shaft of the motor, a fly wheel located adjacent the first mentioned wheel, a disc movably attached to the fly wheel having a gripping pad movably located around its outer edge and between it and the fly wheel, and means for moving the fly wheel whereby the gripping pad may be brought into contact with the first mentioned wheel.

3. A motor attachment of the class described comprising, in combination with a motor, a wheel secured to the shaft of the motor, a fly wheel located adjacent the said wheel, a cone shaped disc movably attached to the fly wheel, a gripping pad movably located inside the fly wheel with a part thereof extending between the disc and the fly wheel and another part projecting beyond the said disc, and means for moving the fly wheel whereby the gripping pad may be brought into contact with the first mentioned wheel.

4. A motor attachment of the class described comprising in combination with a motor, a wheel secured to the shaft of the motor, a fly wheel located adjacent the said wheel, a cone shaped disc movably attached to the fly wheel having a gripping pad movably located around its outer edge and between it and the fly wheel, and means for moving the fly wheel whereby the gripping pad may be made to contact with the first mentioned wheel.

5. A motor attachment of the class described comprising, in combination with a

- motor having a shaft, a wheel secured to the motor shaft, a fly wheel located adjacent the said wheel and a flexible cone shaped disc movably attached to the fly wheel having a gripping pad movably located around its outside edge with a part thereof located between the disc and the fly wheel, and means for moving the fly wheel whereby the gripping pad may contact with the first named wheel. 20
6. A motor attachment of the class described comprising, in combination with a motor having a shaft, a wheel secured to the shaft, a fly wheel located adjacent the said wheel having a flexible cone shaped clutch member movably attached to the fly wheel having a gripping pad attached thereto and located between the fly wheel and the first mentioned wheel, and means for moving the fly wheel whereby the fly wheel and first mentioned wheel may be made to contact with the gripping pad. 25
